UNITED STATES PATENT OFFICE.

EUGENE BUSH AND DOROTHY BUSH, OF WASHINGTON, DISTRICT OF COLUMBIA.

VALVE CONSTRUCTION.

1,265,170.

Specification of Letters Patent. Patented May 7, 1918.

Application filed March 20, 1917. Serial No. 156,098.

To all whom it may concern:

Be it known that we, EUGENE BUSH and DOROTHY BUSH, citizens of the United States, residing at Washington, in the District of Columbia, have invented certain new and useful Improvements in Valve Constructions; and we do hereby declare the following to be a full, clear, and exact description of the invention, such as will enable others skilled in the art to which it appertains to make and use the same.

Our invention relates to valve construction and more particularly to float valves as commonly employed upon flushing tanks of various kinds, and our prime object is to provide reliably efficient means whereby the valve seat may be readily removed when worn and replaced without removing or disturbing the other parts.

A further object, among others, is to provide reliably efficient means whereby the valve seat alone may be quickly removed and reground, if desired, or replaced with a new seat without in the least degree disturbing the relationship of the discharge pipe to the tank lining.

Other objects and advantages will be hereinafter made clearly apparent in the following specification and by reference to the accompanying drawings, in which—

Figure 1 shows our improved float valve complete.

Fig. 2 shows a side view of our valve seat removed.

Fig. 3 shows a top plan view of the valve seat illustrated in Fig. 2.

Figs. 4 and 5 show another form of mounting the valve seat.

In the construction of float valves now in common use, the outlet tube is provided with an upper flared end forming the valve seat and as said parts are integrally formed or cast in one piece, it follows that when the valve seat becomes worn, it is necessary to remove the entire device and after this form of valve has been locked in place for a year more or less, it is found from experience that the act of removing the valve destroys the contiguous part of the tank lining which would have remained in good condition for years longer if left undisturbed.

Our purpose therefore is to provide a removable seat for the outlet tube, which seat may be readily removed from its adjusted position for the purpose of being reground

or replaced by another seat, and this removal of the valve seat proper is readily accomplished without the employment of a wrench for that purpose, thereby avoiding the incidental danger of moving the outlet tube relative to the tank lining and contiguous parts. Furthermore, it will not be necessary to entirely empty the tank of water or cut off the water supply thereto in order to remove and replace our valve seat after it has become worn. In replacing the valve of ordinary construction, it is not only necessary to turn off the water but to thoroughly wipe out or dry the lining of the tank prior to removing the outlet tube.

Referring in detail to the various parts of our invention and co-operating accessories, numerals will be employed, the same numeral applying to a corresponding part in the several views.

Referring in detail to the drawings, 1 indicates the bottom of a tank of the usual or any preferred construction, while 2 designates the lining thereof and 3 the outlet tube of the valve having the usual vent tube 4 extending upwardly in the tank above the normal water line. We prefer to form the integral extension 5 upon the outlet or discharging tube 3 in which the vent tube 4 may be seated as by threading the same therein, it being understood that the extension 5 is provided with a throat 6 to afford communication between the discharging tube 3 and the vent tube 4, as is obviously necessary.

The discharge tube 3 is provided with the enlarged terminal or head indicated by the numeral 7, thereby affording a shoulder 8 adapted to rest upon the gasket 9 and also affording a reliable seating for our removable valve seat 10. The discharge tube 3 is mounted in the bottom of the tank substantially in the usual manner as by the lock nut 11 co-operating with the exterior threads 12 of said discharge tube, whereby the parts 100 may be securely locked together. We prefer also to interiorly thread the upper end of the head or extension 7, whereby the threaded body portion 13 of our valve seat 10 may be received and forced in close contact with the sealing gasket 14 seated upon an annular shoulder within the head or extension 7, as will be desirable. The peculiar location thus provided for the sealing gasket 14 is of such character as to prevent the 110

water from coming in contact therewith with the exception of its outer edge, thus preserving the life and efficiency of the gasket indefinitely.

- 5 If desired, the threads of the body portion 13 may be dispensed with and in lieu thereof two or more inclined ribs or mutilated threads 15 may be formed thereon, the inclined upper faces of which are designed 10 to pass under corresponding faces of the projection of lips 16 carried by a contiguous part of the interior wall of the head 7, it being understood that the interior threads are also omitted. This construction is illustrated in detail in Figs. 4 and 5, as will be 15 observed.

It will be understood that two or more of the coöperating devices 15 and 16 may be provided at equidistant points and that a 20 very limited rotation of the valve seat after the parts 15 and 16 have been brought into engagement with each other will therefore be all that is required to securely lock the seat in an adjusted position or permit said seat to be removed. We therefore reserve 25 the right to employ either the threads referred to for seating our removable valve seat or the coöperating members 15 and 16 as we may find most satisfactory in practice, 30 and we therefore do not wish to be confined to either method.

Ordinarily it will be found practical for the operator to quickly remove our improved valve seat by grasping the same with the 35 hand, but in the event of this operation being difficult from any cause, the interiorly projecting lugs 17 are formed upon the valve seat to facilitate the removal thereof by a spanner wrench or other suitable means.

40 We are aware that it is old to provide removable valve seats for various kinds of valves but we desire to call attention to the simplicity of construction which we have adapted in providing a removable seat for a float valve, inasmuch as the use of our improved valve renders it wholly unnecessary to disturb the relationship of the discharge tube and the tank or the lining thereof after the said discharge tube has been locked in 45 place. In practice, it has been found, when the locking or follower nut 11 is released and the discharge tube removed for the purpose of replacing it with a new one, that the separation of the gasket from the contiguous 50 part of the tank lining will disclose such a corroded condition of the lining as to render the entire tank of no further use until a new lining has been replaced therein, whereas if the discharge tube had not been disturbed 55

60 relative to the tank lining, the life and usefulness of the tank could have been preserved many years longer, especially since in removing the discharge tube 3, it is necessary to empty the tank of its contents and carefully 65 wipe the lining thereof dry, which act

of drying incidentally loosens the corroded spots in the lining and thereby causes general leakage thereof.

It follows therefore that by providing a valve seat which may be quickly removed 70 and replaced, it is rendered wholly unnecessary to disturb the relationship of the discharge tube and the tank lining, thus making it possible to continue the use of the tank indefinitely, thereby rendering the services 75 of an expert plumber unnecessary, a most important desideratum. Moreover, attention is called to the fact that in removing the entire discharge tube, its connection with the spud of the closet often entails a large 80 amount of damage and consequent additional work and expense.

Our improved valve is mounted in the usual manner by locking the same in position by means of the follower nut 11 after the 85 shoulder 8 is brought upon the sealing gasket 9. The float valve 18 is provided with the usual controlling stem 19 coöperating with the bracket or arm 20 upon the tubular vent 4. It is well known that in some 90 instances the action of the water upon the valve seal is so destructive that the efficiency of the valve is destroyed in a few months, whereby a continual leakage results. In the old form of valve it is necessary to call in 95 the services of an expert plumber to remedy the defect, whereas by the use of our improved valve having an easily removable seat, the layman may quickly remove the seat and have it reground or he can replace it 100 with another seat purchasable in the open market as part of his supplies. We desire therefore to call particular attention to the importance of leaving the discharge tube and the lining of the tank undisturbed, 105 whereby the usefulness of said parts is continued practically indefinitely, our improved valve seat rendering said disturbance wholly unnecessary and at the same time providing means for easily preventing all leakage of 110 the valve, as above set forth.

While we have described the preferred construction and combination of parts, we wish to comprehend in this application all substantial equivalents and substitutes that 115 may be considered as falling fairly within the scope of our invention, and we therefore do not wish to be confined strictly to the exact showing herein presented. Believing that the advantages, construction and manner of using our invention have thus been 120 made apparent, further description is deemed unnecessary.

What we claim is:—

1. In a device of the character specified, 125 the combination with an outlet pipe for a flush tank, a head upon said outlet pipe within said tank provided with securing means, a metallic valve seat comprising a straight lower portion provided with securing means 130

- for engaging the securing means of said head, and an outwardly flared upper portion to provide a valve seat and also a hand or tool gripping rim to readily remove and replace said valve seat, and a ball valve coacting with said valve seat and slidably mounted in a support positioned remotely from and independently of said valve seat and said head, whereby to readily and remotely 5 elevate said ball valve independently of said valve seat to provide for the ready removal and replacing of said valve seat only relative to said head and without the removal of any other parts.
- 10 15 2. In a device of the character specified, the combination with an outlet pipe for a flush tank, a head upon said outlet pipe within said tank provided with an annular shoulder to receive a gasket and securing means above said shoulder, a metallic valve seat comprising a straight lower portion provided with securing means for engaging the securing means of said head and an out-
- wardly flared upper portion to provide a valve seat and also a hand or tool gripping 25 rim to readily remove and replace said valve seat, an overflow pipe upon one side of said head, a guide bracket upon said overflow pipe extending to a point remotely above and independently of said valve seat and 30 said head, and a ball valve coacting with said valve seat and having a stem slidably supported through said guide bracket, whereby to readily and remotely elevate said ball valve independently of said valve seat to 35 provide for the ready removal and replacing of only said valve seat from and upon said head.
- 35 40 In testimony whereof we have signed our names to this specification in the presence of two subscribing witnesses.
